UNITED STATES PATENT OFFICE.

JOSEPH JACKSON FOLKS, OF LEVY COUNTY, FLORIDA.

TIRE-TIGHTENER.

SPECIFICATION forming part of Letters Patent No. 633,825, dated September 26, 1899.

Application filed November 19, 1896. Serial No. 612,785. (No model.)

To all whom it may concern:

Be it known that I, JOSEPH JACKSON FOLKS, a citizen of the United States, residing in the county of Levy, State of Florida, have invented new and useful Improvements in Tire-Tighteners; and I do hereby declare that the following is a full, clear, and exact description thereof, reference being had to accompanying drawings by the figures of reference marked thereon.

This invention relates to tire-tighteners, and has for its object to provide a simple and improved device adapted to adjustably connect the ends of the tire and having means for preventing lateral displacement thereof and for filling the space which may occur between the opposite ends of the tire.

To these ends the present invention consists in the combination and arrangement of parts, as will be hereinafter more fully described, shown in the accompanying drawings, and particularly pointed out in the appended claims.

In the drawings, Figure 1 is a perspective view of a portion of a wheel rim and tire having the invention applied thereto. Fig. 2 is a longitudinal sectional view thereof. Fig. 3 is a transverse sectional view taken on the line $\alpha\alpha$, Fig. 2. Fig. 4 is a detail perspective view of the casing or housing. Fig. 5 is a detail perspective view of one of the adjustable heads. Fig. 6 is a detail perspective view of one of the filling-plates.

Corresponding parts are designated by like reference characters in all the figures of the drawings.

Referring to the accompanying drawings, 1 designates a casing or housing of segmental shape adapted to be interposed between the adjacent ends of the opposite felly-sections 2 and 3 to bridge the space therebetween and form a support for the opposite ends of the tire 4. By reference to Fig. 4 of the drawings it will be seen that the housing 1 is in the form of a casing having opposite longitudinal flat sides 5 of segmental shape and opposite end pieces 6, connecting the side pieces, whereby a housing is formed having open outer and inner sides. The opposite ends of the segmental side pieces project beyond the end pieces 6, forming outstanding flanges 7, whereby sockets are provided at the opposite ends of the housing for the reception of the ends

of the respective felly-sections 2 and 3, and the flanges 7 are adapted to hold the housing 55 against being displaced transversely, as will be understood. The outer longitudinal edges of the opposite side pieces 5 are each provided with an inwardly-extending flange 8, and arranged between the said sides is a segmental brace-bar 9, having its opposite ends connected to the respective end pieces 6. By reference to Fig. 2 it will be seen that the outer edges of the side pieces 5 and the brace-bar 9 are arranged in the same plane, so as to 65 provide an evenly-rounded upper face for the housing and permit of the ends of the tire resting flat upon the same.

Each end of the tire is provided with a 70 slidable head 10 of segmental form and adapted to be slidably mounted within the casing or housing 1. These heads are duplicates in construction, and therefore a description of one will be sufficient. Referring to Fig. 5 of the drawings, it will be seen that the head is 75 provided with a pendent ear or shoulder 11, flush with one end of the head and having a bolt-opening 12, provided through the ear near its lower end. Extending longitudinally through the upper face of the head and intermediate of the sides thereof is a groove 13, and the opposite upper edges of the head are each provided with an L-shaped groove 14, extending parallel with the intermediate groove 13. The opposite shoulders 15, provided between the intermediate grooves 13 and the respective L-shaped grooves 14, are each provided with vertical bolt-openings 16, extending entirely through the head. Two heads formed as described are adapted to be 80 arranged within the housing 1, with the shoulders or ears 11 arranged adjacent to each other and projecting beyond the concave side of the housing, each head being secured to the respective end of the tire by means of 85 bolts or suitable fastenings 17, passing through the bolt-openings 16, formed in the head, and having the fastening-nuts 17^a, located within the housing, so as to be effectively protected against being accidentally turned, 90 and the heads of the bolts being countersunk in the outer face of the tire. When the head are thus connected to the tire, each intermediate groove 13 is adapted to receive the brace-bar 9 of the housing, and the opposite L-shaped grooves 14 receive the opposite lon-

itudinal flanges 8, whereby the head is guided in its movement. The ears are connected by means of a bolt 18, passing through the bolt-openings 12, formed therein, and provided with a nut 19, adapted to bear against the outer face of one of the ears, whereby the heads may be adjusted, as will be understood. By reference to Fig. 2 it will be noted that the bolt-opening in one of the ears 11 is angular in form, so as to receive the angled portion of the bolt 18, adjacent to the head thereof, whereby said bolt is prevented from being turned by the operation of the nut 19. Also the bolt-opening 20 in the other ear 11 is larger in diameter than the bolt, so as to permit ready adjustment of the heads and provide for any lateral movement there may be between the same.

In some instances the opposite ends of the tire may not come entirely together, and to fill up the space between the same, so as to form a continuous tire, I provide filling-plates 21, one of which is shown in detail in Fig. 6 and is provided with a pair of substantially L-shaped lugs or hooks 22, extending from one face of the plate near the opposite ends and at opposite edges thereof. By reference to Fig. 3 it will be seen that these L-shaped lugs or hooks are adapted to engage or overlap the longitudinal flanges 8, provided upon the housing 1, whereby the plates are effectually held in place and prevented from being displaced laterally or otherwise.

The present construction and arrangement of parts provide an exceedingly practical and durable form of tire-tightener in which the parts are effectively inclosed and protected by the housing, the ends of the tires being held against the housing and protected against lateral displacement, and the ends of the felly-sections are seated in the socketed ends of the housing, so as to retain the latter firmly in position.

Changes in the form, proportion, size, and the minor details of construction within the scope of the appended claims may be resorted to without departing from the spirit or sacrificing any of the advantages of this invention.

What I claim is—

50 1. In a tire-tightener, the combination with a housing having inner and outer open sides, of opposite slidable heads mounted within the housing, adapted to be connected through one of the open sides of the housing and to the respective ends of the tire, and having ears or shoulders projecting through the opposite open side of the housing, and means adjustably connecting the ears and located exteriorly of the housing, substantially as shown and described.

2. In a tire-tightener, the combination with a housing, of a pair of slidable heads adapted to be connected to the respective ends of the tire and provided with shoulders or lugs having aligned bolt-openings, a bolt having an angular portion and adapted to be fitted in said openings, and a nut or the like carried

by the bolt and adapted to engage one of the ears or shoulders, whereby the heads may be adjusted, one of the bolt-openings being angular and adapted to receive the angled portion of the bolt, and the other bolt-opening being larger in diameter than the bolt to permit of lateral play, substantially as shown and described. 75

3. In a tire-tightener, the combination of a housing or casing open throughout its outer side and provided with a longitudinal brace-bar located intermediate of the opposite lateral closed sides of the housing, slideable heads mounted within the housing and provided with longitudinal grooves adapted to slidably receive the brace-bar, said heads being adapted to be connected through the open side of the housing to the respective ends of the tire, and means for adjustably connecting the heads, substantially as shown and described.

4. In a tire-tightener, the combination of a housing or casing open at its outer side and provided with longitudinal flanges extending inward at the open side of the housing, and opposite slideable heads provided with opposite grooves adapted to receive the respective longitudinal flanges of the housing, said heads being adapted to be connected through the open side of the housing and to the respective ends of the tire, substantially as shown and described. 95

5. In a tire-tightener, the combination of a housing open throughout its outer longitudinal side and provided with a longitudinal brace-bar located intermediate of the opposite lateral closed sides of the housing, and longitudinal flanges projecting inward at the open outer side of the housing, opposite slideable heads mounted within the housing and adapted to be connected through the open side thereof and to the respective ends of the bar, each head being provided with a longitudinal groove located intermediate of the sides thereof, and opposite longitudinal grooves provided in the side edges of the head, the intermediate grooves being adapted to receive the longitudinal brace-bar, and the opposite side grooves to receive the longitudinal flanges of the housing, substantially as shown and described. 110

6. In a tire-tightener, the combination of a casing open throughout its outer side and provided with longitudinal flanges projecting inward from the opposite closed sides and at the open outer side of the housing, means for adjustably connecting the ends of the tire, and filling-plates adapted to be fitted between the ends of the tire and provided with opposite L-shaped lugs or hooks adapted to engage the respective longitudinal flanges of the housing, substantially as shown and described. 120 125
